UNITED STATES PATENT OFFICE.

LEWIS WARRINGTON CHUBB, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL PRECIPITATING SYSTEM.

1,399,422.

Specification of Letters Patent.

Patented Dec. 6, 1921.

Application filed March 9, 1918. Serial No. 221,397.

To all whom it may concern:

Be it known that I, LEWIS WARRINGTON CHUBB, a citizen of the United States, and a resident of Pittsburgh, in the county of 5 Allegheny and State of Pennsylvania, have invented a new and useful Improvement in Electrical Precipitating Systems, of which the following is a specification.

My invention relates to electrical precipitating systems of a character that may be 10 used for precipitating suspended particles from a vapor or gas.

In such systems, it is usual to provide a central discharge electrode capable of emitting 15 non-disruptive electrical discharges, by means of which discharges the suspended particles in the gas or vapor being treated are charged and are, thereafter, attracted to the oppositely-charged wall of a containing 20 structure known, in the smoke precipitating art, as the collecting electrode. When sufficient particles have been thus attracted to the walls of the treating chamber or collecting electrode, the mass thereby formed 25 detaches itself and falls to the bottom of the chamber.

In order to provide such silent electrical discharges from a central discharge electrode and thereby impart charges to the 30 suspended particles, it has hitherto been necessary to impress upon such discharge electrode a potential of very high value. Since it is impractical to generate a direct-current voltage of sufficiently high value for 35 such service, the usual practice has been to supply such a precipitating system with a high alternating-current voltage and then rectify the same, by means of a mechanical rectifier. The difficulties involved in sub- 40 jecting mechanical rectifiers to service conditions requiring the use of such high voltages are numerous and well known, and it is highly desirable to avoid the use of the same, if possible.

By my invention, I, therefore, propose to 45 utilize the system herein described in which a relatively low direct-current voltage may be employed in an electrical precipitating system to cause silent electrical discharges 50 from an active electrode and thus avoid the difficulties attendant upon the use of high voltages.

It is well known that, when a negative potential is impressed on a highly heated

or incandescent body, electrons are emitted 55 therefrom and thermionic currents are caused to flow, even though the potential impressed on such heated electrode has an extremely low value. By "thermionic currents" I refer to currents which are initiated 60 by the discharge of electrons from a heated body or by chemical reaction. When such a heated body is employed as a discharge electrode and is positioned in a suitable chamber through which a gas or vapor, in 65 which solid or fluid particles are suspended, is passing, the electrons emitted by such a heated electrode cause thermionic currents to flow across the path of such suspended particles. A negative charge is thereupon 70 imparted to the suspended particles and, if the wall of the containing member be positively charged, it will act as a collecting electrode and the negatively charged particles will be attracted thereto. When a 75 sufficient number of particles have become attached to the collecting electrode, the mass will detach itself and fall to the bottom of the stack.

My invention therefore provides for the 80 use of such an incandescent or heated discharge electrode to obtain such thermionic currents and the subsequent charging and precipitation of the particles in a precipitating system in which a relatively low direct-current potential may be impressed on said 85 system directly from a source of direct-current energy of relatively low voltage without using any of the intermediate apparatus made necessary by the employment of a 90 high-potential alternating-current voltage.

For a better understanding of the nature of my invention, reference may be had to the drawing, in which Figure 1 is an elevational view of a discharge electrode conforming to my invention and positioned in the treating chamber (shown in section) of a smoke precipitating system, while Figs. 2, 3, 4 and 5 are fragmentary elevational views of various modifications of my discharge 95 electrode.

Referring more particularly to Fig. 1, a smoke-precipitating device is shown at 1. Within a treating chamber or smoke-stack 2, which constitutes a collecting electrode, is 100 positioned a hollow perforated discharge electrode 3. By means of the lead wires 5 and 6, a suitable direct-current voltage from 105

a generator 4 is impressed on the central discharge electrode 3 and the collecting electrode 2. A properly proportioned mixture of gas and air or other combustible material 5 is fed into the interior of the hollow electrode 3 by means of a supply pipe 7.

The combustible mixture which is fed into the interior of the hollow electrode 3, after passing through perforations 3^a with which 10 said discharge electrode is provided, is ignited at the surface thereof, thereby providing an incandescent or hot cathode member and causing the emission of electrons which give rise to the flow of thermionic currents.

15 Fig. 2 shows a modification of the discharge electrode shown in Fig. 1, in which the perforations are arranged in an annular manner at spaced intervals along said electrode.

20 Fig. 3 represents a discharge electrode which may be used in the preferred embodiment of my invention.

It may often be desirable to so construct the discharge electrode as to shield the flame 25 blasts used to heat the surface of said electrode from the draft caused by the gas or vapor passing upward through the treating chamber. With this end in view, I have provided the electrode with annular recesses 30 8 in which are disposed rings of refractory material 9 and have further provided the recesses with perforations from which a plurality of flame blasts may impinge on said rings of refractory material to heat the same 35 to a high temperature. Such an annular ring of refractory material, being conducting when very hot or in an incandescent state, will give off a relatively large number of electrons which will cause thermionic currents to flow quite abundantly even when 40 a relatively low potential gradient is impressed between the discharge electrode and the collecting electrode. More electrons can be produced with the same degree of heat by 45 adding suitable quantities of thoria, zirconia or other refractory oxids to the material of which the ring 9 is composed.

Fig. 4 shows a further modification of the 50 central discharge electrode the function of which was explained in connection with Fig. 1. In this modification, sections of granular refractory material are arranged along the length of the electrode. Into these are introduced, from the interior of the electrode, 55 a suitable explosive mixture of gas and air, such a mixture producing an incandescent body of very high temperature.

In Fig. 5 a modification of the discharge 60 electrode is shown which has a central conducting member 11 surrounded by refractory material 12. When current is passed through the conducting member 11, the refractory material in proximity thereto is raised to a high temperature, causing the 65 emanation therefrom of electrons and the

consequent flow of thermionic currents in the treating chamber.

The operation of my invention is as follows:

The gas or vapor to be treated is caused to 70 pass, by natural draft, upward through the treating chamber and between the discharge electrode 3 and the collecting electrode 2. A low negative potential is then impressed on the heated central discharge electrode 3, 75 whereupon the thermionic currents which flow between the electrodes impart to the particles suspended in the vapor or gas being treated a negative charge. These particles are then attracted by the positive charge 80 of the collecting electrode 2 and, after a sufficient number of them have lodged thereon, the resultant mass is detached and falls to the bottom of the chamber.

While I have shown and described a number 85 of embodiments of my invention, it will be apparent to those skilled in the art that many further modifications may be made therein without departing from the spirit and scope of the appended claims. 90

I claim as my invention:

1. In an electrical precipitating system, the combination with a treating chamber and a discharge electrode positioned therein and having a plurality of annular recesses, of 95 thermal means for causing thermionic currents to flow from said discharge electrode upon the application of potential to the same, said thermal means consisting of flame blasts to heat said electrode to incandescence 100 in the vicinity of said recesses.

2. In an electrical precipitating system, the combination with a treating chamber and a discharge electrode positioned therein and having a plurality of annular recesses, of 105 refractory material positioned in said recesses and thermal means for causing thermionic currents to flow from said refractory material upon the application of potential to said electrode, said thermal means consisting of flame blasts produced by, and heating, said refractory material to incandescence. 110

3. In an electrical precipitating system, the combination with a treating chamber, of 115 a discharge electrode positioned therein, said electrode having sections of refractory material and being provided with perforations through which heat may be applied to said refractory portions for raising said 120 portions to incandescence.

4. In an electrical precipitating system, the combination with a treating chamber, of a discharge electrode positioned therein, said electrode having sections of refractory material and being provided with perforations through which heat may be applied to said refractory portions to cause said portions to emit silent electrical discharges. 125

5. In an electrical precipitating system, 130

- the combination with a treating chamber, of a discharge electrode positioned therein, said electrode having sections of refractory material and being provided with perforations 5 through which heat blasts may impinge upon said refractory portions disposed in proximity to said electrode, whereupon said refractory portions are raised to incandescence, thereby causing the flow of thermionic currents.
6. In an electrical precipitating system, the combination with a treating chamber, of a discharge electrode positioned therein and having a plurality of flame-emitting openings positioned entirely below the electrode 15 surface.
7. In an electrical precipitating system, the combination with a treating chamber, of a discharge electrode positioned therein 20 and having a plurality of flame-emitting openings positioned below the electrode surface and a member of refractory material positioned to receive the flame blasts.
8. In an electrical precipitating system, 25 the combination with a treating chamber, of a discharge electrode positioned therein and having an annular recess and a plurality of openings in a wall of said recess and a ring of refractory material located in said 30 recess.
9. In an electrical precipitating system, the combination with a treating chamber, of a discharge electrode positioned therein and having an annular recess and a ring 35 of refractory material located in said recess, a plurality of flame-emitting openings being provided in the walls of said recess.
10. In an electrical precipitating system,
- the combination with a treating chamber, of a discharge electrode positioned therein and 40 having an annular recess and a ring of refractory material located in said recess, a plurality of rows of flame-emitting openings being provided in the walls of said recess respectively above and below said 45 ring.
11. A discharge electrode having a plurality of openings positioned entirely below the electrode surface and adapted to emit flame. 50
12. A discharge electrode having an annular recess, a plurality of openings in a wall of said recess and refractory material located in said recess.
13. A discharge electrode having a plurality of annular recesses, a plurality of openings in the walls of said recesses and a plurality of rings of refractory material positioned in the respective recesses. 55
14. A discharge electrode having an annular recess and a plurality of openings in the walls of said recess. 60
15. A discharge electrode having an annular recess, a plurality of rows of openings in the walls of said recess, and a ring of non-metallic material located within said recess between said rows. 65
16. A discharge electrode having a plurality of openings adapted to emit flame and refractory material positioned near said 70 openings.

In testimony whereof, I have hereunto subscribed my name this 28th day of Feb., 1918.

LEWIS WARRINGTON CHUBB.
